UNITED STATES PATENT OFFICE.

LEONARD L. ELDEN, OF DORCHESTER, MASSACHUSETTS, ASSIGNOR, BY MESNE ASSIGNMENTS, TO GENERAL ELECTRIC COMPANY, A CORPORATION OF NEW YORK.

MECHANISM FOR THE CONTROL OF CIRCUIT-BREAKERS.

1,157,930.

Specification of Letters Patent.

Patented Oct. 26, 1915.

Original application filed June 20, 1901, Serial No. 65,241. Divided and this application filed December 2, 1903. Serial No. 183,457.

To all whom it may concern:

Be it known that I, LEONARD L. ELDEN, a citizen of the United States, and residing in Dorchester, in the county of Suffolk, in the State of Massachusetts, have invented an Improvement in Mechanism for the Control of Circuit-Breakers, of which the following description, in connection with the accompanying drawings, is a specification, like letters on the drawings representing like parts.

My invention is an improvement in automatic circuit breakers and relates more particularly to the tripping mechanism and to the automatic releasing thereof or cutting off of control of the operating member, my present application being a division of the application filed June 20, 1901, Ser. No. 65,241.

In the drawings, in which I have illustrated a preferred embodiment of my invention, Figure 1 shows one form of my circuit breaker in side elevation, parts being broken away for clearness of illustration, and shows in dotted lines the position assumed when the circuit is broken or the breaker is open. Fig. 2 is a detail in side elevation of a portion of the tripping device, and Fig. 3 is an enlarged perspective view, parts being broken away, showing details of the operating mechanism. Fig. 4 is a fragmentary view in end elevation showing the coöperating contacts.

For convenience of illustration, I have shown one of my improved circuit breakers in position on a switch board A.

As herein shown, a bracket a^8 , whose head a^9 is bolted to the switch board, supports the rear portion of the circuit breaker by means of vertical insulating posts a^{10} carrying at their lower ends a base block a^{12} of wood, ebonite, or other proper insulating material.

The block a^{12} carries on its upper side usual contacts a^{13} in pairs, there being herein shown three pairs thereof, adapted to receive the wires from a three phase generator, or the wires of any other three circuits which may be inter-related in such a manner that it is desirable to make and break the same simultaneously.

Each contact spring a^{13} connects with a conductor or post a^{14} for receiving the circuit wires.

Arranged to coöperate with the contacts a^{13} are corresponding sets of contact makers a^{15} secured in proper position on an insulating bar a^{20} arranged to slide up and down on the stationary posts a^{10} and operated by links a^{21} connected thereto at their lower ends, and, at their upper ends, connected at a^{23} to the free end of a bell crank a^{24} pivoted at a^{25} in ears a^{26} extending rigidly from the bracket a^8 .

The opposite end of the bell crank is bifurcated, and the opposite free ends thereof provided with a roll a^{27} , operating in a slot a^{28} in a collar a^{30} of a plunger or reciprocating rod a^{31} which is arranged to slide in a bearing a^{32} provided for convenience in the bracket a^8 .

The plunger a^{31} passes out through the head a^9 and through a plate a^{33} , secured in a similar manner to the front side of the switch board A, and is normally held under a tendency to move inwardly by means of a powerful spring a^{34} which bears against the collar a^{30} .

The plunger a^{31} is connected with a toggle device, which, however, is not herein claimed, as it and also the other features herein shown and not claimed, are duly claimed in my aforesaid application and also application Ser. No. 184,648, filed December 10, 1903. This toggle is composed of opposite pairs of links a^{35} , a^{36} , pivoted to each other at a^{37} and connected together by a bridge a^{38} , and at their opposite ends pivoted respectively at a^{39} to brackets a^{40} and at a^{41} to the extreme projecting end of the plunger a^{31} , and normally maintained with a downward tendency by a spring a^{40} .

The plunger a^{31} is provided with a slot a^{42} in which operates the upper free end a^{43} of an actuating handle or lever a^{44} pivoted at a^{45} to the brackets a^{10} and arranged to engage a bearing, herein shown as a roller a^{46} , mounted in the slot a^{42} of the plunger. This actuating device constitutes an important feature of my present invention residing in so arranging and connecting the actuating member or lever a^{44} and the plunger a^{31} that when the lever is pulled down by the operator it will automatically break and become inoperative, thereby rendering it impossible for the operator accidentally to lock the switch closed until the circuits

are in safe, normal condition, as will be presently described. For this purpose the portion a^{43} of the lever is separate from the rest of the lever, being pivoted at a^{45} , and provided with a locking pawl or latch a^{47} normally in engagement with a notch a^{48} in a part a^{49} of the lever a^{44} , said two parts being held together by a spring a^{50} . When the lever is pulled forward to its dotted line position, Fig. 2, the lower end of the latch a^{47} strikes against a stop a^{51} , and is thereby disengaged from the part a^{49} of the lever so that the downward pull on said part has no control whatever on the part a^{43} and accordingly the plunger a^{31} is thus automatically placed beyond the control of the operator.

My invention also enables the operator to ascertain at any moment whether the line has been restored to normal (after having been automatically tripped for instance) by a simple movement of the actuating lever, inasmuch as the operation of the lever serves to actuate the plunger a^{31} , which will thereupon be automatically locked in closed position (by means of the toggle mechanism) if the difficulty has been removed, but, if the difficulty has not been removed, the plunger cannot be automatically locked (because of the automatic tripping mechanism, presently to be described), and hence, upon the automatic escape therefrom of the actuating lever, said plunger will automatically fly back to open position. In other words, I provide a construction in which a single hand-lever at all times whenever the line is in normal condition. When the part a^{49} has been pulled down to close the circuit breaker and an overload has immediately opened the latter, the part a^{43} is moved to the full line position, Fig. 2 and the locking pawl or latch a^{47} automatically reengages the part a^{49} when the operator releases the latter.

The toggle at its pivot a^{37} is provided with a laterally extending pin a^{52} , in position, when the toggle is extended, to engage the upper eccentric side a^{53} of a device herein shown for convenience as a lever a^{54} pivoted at a^{55} to the adjacent bracket a^{40} and preferably provided with an adjusting screw a^{56} for regulating the normal height of the surface a^{53} which engages the pin a^{52} , and having a projecting end or arm a^{57} in position to be engaged and raised by any suitable automatic actuator. The actuator which I have shown is of the ordinary solenoid type consisting of a coil b carried by brackets b^1 on the switch board.

In the coil b operates a suitable core b^2 carrying at its lower end a projection or plate-armature b^3 , and guided on rods b^4 , said plate b^3 projecting in line with the end a^{57} of the lever a^{54} , so that when any accident occurs, such as a short circuit or other

trouble tending suddenly to increase the current or cause liability of fire or other danger due to a sudden rush of current, the increased current flowing through the coil b will instantly raise the core b^2 and armature, 70 and thereby lift the eccentric surface a^{53} so as to raise the toggles above their dead center, permitting the spring a^{34} instantly to move inwardly the plunger a^{31} which (see Fig. 1) serves to turn the bell crank a^{24} upwardly and thereby raise the bar a^{20} and simultaneously cut out or break the circuits connected with the circuit breaker thus operated.

It will, of course, be understood by those skilled in the art that the details of wiring and general arrangement will be varied according to the particular situation, and, as already intimated, neither is my invention restricted to the kind of circuit breaker 85 herein shown.

The adjustment of the height of the eccentric surface a^{53} , herein shown as accomplished by means of the set screw a^{56} , although it will be understood that any other suitable means of adjustment may be employed within the spirit of my invention, is for the purpose of giving the circuit breaker any degree of sensitiveness or responsiveness, as, for instance, if the trouble is only 95 momentary, as when two line wires might swing together and immediately swing apart again, it might be desirable that the breaker should not operate and hence the surface a^{53} would be adjusted to a low position, so as to render the operation of the circuit breaker not readily responsive, and hence, although the increase of the current through the coil b , would raise the armature b^3 into contact with the lever a^{54} , it would drop down again 100 instantly, and would not have had time to raise the lever a^{54} against the considerable resistance of the toggle device. Also, to enable the breaker to be operated at any 105 predetermined increase of current, I provide on the lever ends of the guides b^4 threaded thumb screws b^{20} , by means of which the core b^2 may be adjusted to correspond to a scale marked thereon, as is clearly shown in the drawings. When the operator

wishes to operate the circuit breaker, he simply pulls down upon the lever a^{44} , thereby closing the circuit breaker, whereupon the lever automatically becomes inoperative 110 leaving the circuit breaker free to open automatically in case any trouble should occur, and if said trouble does occur, it is impossible for the operator to prevent the circuit breaker from staying open by a simple movement of the lever on his part, inasmuch as the moment he lowers the lever a^{44} the plunger flies back automatically to open position, as, the surfaces a^{53} being raised by the excessive current in the solenoids, the 115 circuit breaker cannot become locked.

Having described my invention, what I claim as new and desire to secure by Letters Patent, is:—

1. An electric switch, comprising separable contacts, means for closing them, electro-responsive opening means, and means independent of said electro-responsive means to vary the sensitiveness with which said contacts respond to said opening means.

10 2. A switch, comprising separable contacts, closing mechanism therefor, and an operating member movable to actuate said closing mechanism and having provision for disconnection by a continuation of such 15 movement.

3. A switch, comprising separable contacts, closing mechanism therefor, and an operating member constructed to actuate said closing mechanism by a single movement and having provision for self-disconnection at the termination of such movement.

4. An electric switch, comprising separable coöperative contacts, closing means therefor including means normally maintaining said contacts closed when moved to closed position, an operating lever, and automatic means for cutting off control of said operating lever at a predetermined point 30 in the movement of said closing means.

5. In an electric switch, the combination of separable coöperative contacts, means for causing their separation, means for normally restraining the separating means, 35 means including an operating lever automatically disabled by movement into circuit closing position for preventing the maintenance of the separable coöperative contacts in circuit-closing position during the continuance of predetermined electrical conditions in the circuit, and automatic magnetic means for controlling the switch upon the occurrence of said predetermined electrical conditions in the circuit.

45 6. In an electric switch, the combination of separable coöperative contacts, means for causing their separation, means for normally restraining the separating means, means including a swinging, self-breaking lever, for preventing the maintenance of the separable coöperative contacts in circuit-closing position during the continuance of predetermined current conditions, and automatic magnetic means for actuating the switch upon the occurrence of said predetermined current conditions.

7. In an automatic magnetic circuit breaker, separable coöperative contacts, closing means therefor, and electro-responsive means for preventing the maintenance of the contacts in circuit closing relation during the continuance of predetermined current conditions, said electro-responsive means becoming inoperative for said purpose upon the discontinuance of said cur-

rent conditions, means then operating for retaining said contacts closed when actuated by said closing means, and means independent of said electro-responsive means for varying the responsiveness of said retaining means.

10 8. A switch for electric currents, comprising separable contacts to open and close the circuit, and closing mechanism therefor, including an operating handle and means 75 causing the latter to lose control of said contacts every time they are fully closed.

9. A circuit breaker, having make-and-break contacts for controlling a circuit, an operating member therefor, an actuating device for actuating said operating member, and means for automatically placing said operating member beyond the control of said actuating device whenever the circuit-breaker is closed.

10 85 10. A circuit breaker, having make-and-break contacts for controlling a circuit, a longitudinally reciprocating operating member therefor, a swinging actuating device for actuating said operating member, means 90 responsive to movement of said device into circuit closing position for automatically placing said device out of the control of said actuating device during abnormal current conditions, and means coöperating with 95 said member and said device for automatically enabling the latter upon the restoration of normal current conditions to regain control of said operating member, solely by movement of said actuating device.

11. In an electric switch, make-and-break contacts, a multi-part, self-breaking operating lever for opening or closing the switch contacts and automatically disconnected therefrom by movement into switch closing 105 position, latching means responsive to current for normally holding the movable switch contacts in switch closing position and for automatically releasing said contacts independently of the handle, and connections for restoring the switch contacts by the handle independently of said means.

12. In an electric switch, comprising separable coöperative contacts, closing means therefor, a locking device for retaining said contacts closed, automatic magnetic means for controlling the operation of said locking device, an operating lever, and automatic means for cutting off control of said operating lever at a predetermined point in 115 the movement of said closing means.

13. In an electric switch, comprising separable coöperative contacts, closing means therefor, an operating lever, operative at all times to actuate said closing means momentarily, and automatic means for cutting off control of said operating lever at a predetermined point in the movement of said closing means.

14. An electric switch, comprising an op- 130

- erating lever, a movable contact, connections between said contact and lever, a locking toggle connected with said contact, a handle for moving said contact to a limiting position and simultaneously by said movement setting the toggle in locked position, and automatic releasing mechanism to collapse the toggle independently of handle movement.
- 10 15. An electric switch, comprising a movable contact, an actuator therefor, a locking toggle arranged when set to hold the contact closed, means for disengageably connecting said actuator to said movable contact, and 15 automatic magnetic means for opening the circuit independently of the actuator upon the occurrence of predetermined electrical conditions.
16. An electric switch, comprising a contact-carrier member, means for operating said member, a locking toggle for normally holding said member in switch-closed position, and electro-responsive means for breaking said toggle to permit the switch to open, 25 said switch having opening movement independent of the movement of said operating means.
17. An electric switch, comprising a contact-carrying member, a locking toggle connected with said member, an operating handle having detachable connection with said parts, and means having an electro-responsive controlling device for breaking said toggle independently of handle movement.
- 35 18. An electric switch, comprising a contact-carrying member, a toggle connected with said member to coöperate in controlling the same, a lever connected with and operating said toggle and automatically disconnected therefrom at a definite point in its movement, said lever having connections to close the switch, and means having an electro-responsive controlling device for breaking said toggle.
- 45 19. An electric switch, comprising a contact-carrying member, a locking toggle for holding said member in switch closing position when locked, a lever to close the switch and having connections for actuating said toggle, said toggle and lever being constructed and mounted to render the toggle capable of being broken independently of the motion of the lever, and means having an electro-responsive controlling device in coöperative relation to prevent the maintenance of said toggle in circuit-closing position during the continuance of predetermined electrical conditions in the circuit.
- 55 20. An electric switch, comprising separable contacts to open and close the circuit, closing means therefor, and an operating lever provided with mechanical means for automatically placing said closing means beyond the control of said lever when moved to closing position.
21. An electric switch, comprising separable contacts to open and close the circuit, closing means therefor, automatic releasing means responsive to predetermined current to open the switch, and an operating lever provided with mechanical means for automatically cutting off its control over the switch when the latter has been moved to closed position.
22. In an electric switch, automatic magnetic tripping means therefor, and an operating handle for closing the switch, having means normally maintaining inoperative relation between said handle and switch when the latter is closed.
23. An electric switch, automatic magnetic opening means therefor, and an operating handle provided with an automatically-tripped latch for mechanically disconnecting said handle and switch when the latter has been closed.
24. An electric switch, comprising a contact-carrying member, a manual operating device provided with connecting means positively engaging said member for closing the switch, means for automatically disconnecting said lever and member, and electro-responsive means for preventing the maintenance of the switch in circuit-closing position during the continuance of predetermined electrical conditions in the circuit.
25. An electric switch, comprising a contact-carrying member, means for operating said member, closing means permanently secured to said contact-carrying member for connecting said carrying member and operating means, means for automatically disconnecting said closing means and operating means, and automatic means for releasing said closing means from closing position upon the continuance of abnormal current conditions.
26. An electric switch, comprising a contact-carrying member, manually operable means for actuating said member, electro-responsive means for automatically opening said switch, and independent mechanical tripping means for said actuating means for preventing the maintenance of the switch in circuit-closing relation during the continuance of predetermined current conditions.
27. An electric switch, comprising a contact-carrying member, an operating handle for operating said member, a locking toggle connected with said member and having detachable connection with said handle, and electro-responsive tripping means for effecting the release of the toggle to permit the opening of the switch.
28. An electric switch, comprising a contact-carrying member, a locking toggle coöperative in controlling said member, a lever discontinuously connected with and operating said toggle and having connection to close the switch, and electro-responsive trip-

ping means for effecting the release of the toggle to permit the opening of the switch.

29. An electric switch, comprising separable contacts to open and close the circuit, 5 operating means for said contacts, and an actuating handle for actuating said operating means, including two pivotally mounted members, means normally locking said members together, and releasing means for unlocking said members at a predetermined 10 point in their swinging movement and thereby losing control of the operating means.

30. An electric switch, comprising separable contacts to open and close the circuit, 15 operating means for said contacts, and an actuating handle for actuating said operat-

ing means, including two independently movable members, a locking device for normally locking said members in predetermined relation, tripping means mechanically 20 actuated at a definite point in the movement of said handle to release said locking device, and a spring for restoring the members to locked relation.

In testimony whereof, I have signed my 25 name to this specification, in the presence of two subscribing witnesses.

LEONARD L. ELDEN.
